UNITED STATES PATENT OFFICE.

OTTO E. LEINES, OF WINNIPEG, MANITOBA, CANADA.

FIRE-ALARM SYSTEM.

Application filed March 15, 1924. Serial No. 699,521.

This invention relates to fire alarm apparatus and has for its object the provision of a novel thermostatic circuit closer which will operate to close the circuit through an alarm device when the temperature within a room or building to be protected reaches a certain degree.

An important object is the provision of a circuit closer of this character which is so arranged that it may be caused to operate at any desired temperature, a peculiar and novel adjustment being provided for this purpose.

An additional object is the provision of a device of this character which will be simple and inexpensive in manufacture, easy to install, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is an elevation of my circuit closer,

Figure 2 is a vertical section on the line 2—2 of Figure 1,

Figure 3 is a side elevation looking toward the supporting rod for the adjustable element,

Figure 4 is a cross section on the line 4—4 of Figure 1,

Figure 5 is a detail perspective view of the clamp carrying the movable contact and

Figure 6 is a diagram of the electric circuit.

Referring more particularly to the drawing I have shown the device as comprising a supporting base 10 which is of insulating material and which may be a piece of wood, fiber or the like and which is provided with suitable holes 11 for the passage of nails, screws or the like whereby the device may be fastened upon the wall or other location in a building or room to be protected. Mounted on this base is a thermometer tube 12 held in place by suitable brackets 13 and terminating at its lower end in a bulb 14 of any desired size and shape. The tube has the usual bore 15 and contains mercury which rises in the bore in accordance with the expansive effect produced by the action of heat in exactly the same manner as in a thermometer.

Projecting into the bore of the tube near its juncture with the bulb is a contact 16 and projecting thereinto at spaced points throughout its length are similar contacts 17, while at the upper end is another 18 of the same type. All of these contacts may be screws, plugs or their equivalents and connected with the contact 16 is a wire 19 which is brought out to a binding post 20 on the base. The contact 18 is connected with a binding post 21 on the base. The contact 16 is always in engagement with the mercury 22 in the bulb and tube and the other contacts 17 and 18 are successively engaged thereby as the mercury rises in the tube when it expands on account of a rise in temperature.

Mounted in suitable brackets 23 at the opposite edge of the base is a rod 24 on which is engaged a clamp designated broadly by the numeral 25 which may be set at any desired point on the rod. This clamp includes a pair of clamping arms 26 which are formed to grip the rod and which have thumb pieces 27 adapted to be squeezed together to cause the jaws at the ends of the arms to be moved apart so that the clamp may be adjusted along the rod. Carried by this clamp is an elongated spring contact 28 adapted to be engaged against any desired one of the contacts 17, and also carried by the clamp is a short spring 29 which bears against the base for the purpose of preventing the clamp from tilting on the rod.

In the use of the device a wire 30 is connected with a battery or other source of current 31 and is connected with the binding post 20. Connected with a binding post 31 at the top of the rod 24 is a wire 32 which leads to one terminal of an alarm device which in the present instance is shown as a bell 33. Leading from the bell is a wire 34 connected with the other terminal of the battery. This is intended to be the local alarm. Connected with the binding post 21 is a wire 35 which may be led to the city or township fire alarm signal system.

In the operation it is evident that in case of fire the heat will cause the mercury to expand and rise within the tube 12. When the mercury touches the contact 17 engaged by the spring 28, it is evident that the circuit will be closed from the battery, through the wire 31, binding post 20, column of mercury, contact 17 engaged thereby, spring

28, clamp rod 24, and wire 23 through the bell or other signal 33 and back to the battery. In case the mercury reaches the contact 18 which indicates a critical condition 5 the current will be fed through the wire 35 to the signal at headquarters. In installing the device in a house or other building having many rooms, it is evident that one unit should be installed in each room with 10 all units connected in parallel in order to furnish adequate protection.

From the foregoing description and a study of the drawings it will be apparent that I have thus provided a simply constructed and easily installed thermostatic circuit closer which is well adapted for use as a part of a fire alarm system for giving not only a local signal but also sounding or giving any other kind of alarm at a central station or fire head quarters. Owing 20 to the simplicity of the construction and the fewness of the parts it is apparent that there is very little to get out of order so that the device should have a long life and 25 satisfactorily perform all of its functions.

While I have shown and described the preferred embodiment of my invention it is of course to be understood that I reserve

the right to make such changes in the form, construction and arrangement of parts as 30 will not depart from the spirit of the invention or the scope of the subjoined claims.

Having thus described my invention I claim:

1. In a switch of the character described 35 including an elongated member, a contact longitudinally adjustably engaged upon said member, said contact being formed as a split sleeve element provided with oppositely extending arms and provided with 40 diverging wings constituting finger grips.

2. In a thermostatic switch, a thermometer tube carrying contacts, an elongated supporting rod arranged in parallel relation to the thermometer tube, and a contact 45 device carried by the rod and formed as a split tubular member of resilient metal frictionally engaged upon the rod and provided with contact arms, said tubular member having integrally formed diverging 50 wings constituting finger grips whereby the tubular member may be moved longitudinally along said rod.

In testimony whereof I affix my signature.

OTTO E. LEINES.
